CLAIM

The ornamental design for a window cleaning device, as shown and described.

DESCRIPTION

FIG. 1 is a front perspective view of a window cleaning device according to the present disclosure having a pole shown in phantom;

FIG. 2 is a front perspective view of the window cleaning device of FIG. 1;

FIG. 3 is a front view of the window cleaning device of FIG. 2;

FIG. 4 is a rear view of the window cleaning device of FIG. 2;

FIG. 5 is a first side view of the window cleaning device of FIG. 2;

FIG. 6 is a second, opposite side view of the window cleaning device of FIG. 2; and

FIG. 7 is a top view of the window cleaning device of FIG. 2; and,

FIG. 8 is a bottom view of the window cleaning device of FIG. 2.

The broken lines in the drawings illustrating environmental structure or boundaries that form no part of the claimed design.

1 Claim, 8 Drawing Sheets
